UNITED STATES PATENT OFFICE.

CELESTIA M. WINN, OF WATONGA, OKLAHOMA.

BED.

1,339,250.

Specification of Letters Patent.

Patented May 4, 1920.

Application filed February 11, 1919. Serial No. 276,332.

To all whom it may concern:

Be it known that I, CELESTIA M. WINN, a citizen of the United States, residing at Watonga, in the county of Blaine and State 5 of Oklahoma, have invented new and useful Improvements in Beds, of which the following is a specification.

This invention relates to beds and the principal object of the invention is to provide means for adding an extension to the bed for accommodating one or more extra persons.

Another object of the invention is to provide means whereby the extension may be 15 placed under the bed when not in use.

The invention also consists in certain other features of construction and in the combination and arrangement of the several parts, to be hereinafter fully described, illustrated in the accompanying drawings and 20 specifically pointed out in the appended claims.

In describing my invention in detail, reference will be had to the accompanying drawings wherein like characters denote like or corresponding parts throughout the several views, and in which:—

Figure 1 is a view, partly in section, showing the invention.

Fig. 2 is a perspective view with parts broken away of the extension frame.

Fig. 3 is an end view showing the extension located under the bed.

Fig. 4 is a detail view showing the means 35 for connecting the extension to the bed.

Fig. 5 is a view of the mattress used with the invention.

In these views 1 indicates the bed which consists of the head part 2 and the foot part 40 3 connected together by the side rails 4. I prefer that the side rails be of angle form and these rails receive the bed springs, as usual.

5 indicates the extension which consists 45 of a rectangular frame, also made of angle iron. One of the side rails of this extension frame is provided with the U-shaped loops 6 which are adapted to pass through the slots 7 in one of the side rails 4 of the bed. 50 This side rail 4 has pivoted thereto the hooks 8 which are adapted to engage with the loops 6 after they are passed through the slots 7. In this way the extension frame will be connected with the side rail of the bed. The other side rail of the extension

frame has pivoted thereto the legs 9 so that said legs may be swung upwardly against the side rail when the extension frame is to be placed under the bed. The legs are held in folded position by means of the catches 60 9'. Each side of the extension frame is provided with a pair of downwardly projecting parts 10 which are provided with the casters 11 so that when the legs 9 are swung upwardly against the frame and the frame 65 detached from the bed rail and pushed under the bed, the casters will engage the floor as shown in Fig. 1. The legs 9 as well as the legs of the bed may be provided with the customary casters. The extension frame is 70 adapted to support the usual bed springs and these springs may be detachably connected with the springs on the bed by means of hooks 9.

I provide a mattress for the bed and extension which is formed of two parts 13 and 14, as shown in Fig. 5. Each of these parts are provided with the flaps 15, which are of triangular shape with their bases connected with the edges of the two parts. The flaps 80 are alternately arranged on the two parts so that when the two parts of the mattress are placed together the flaps on one part will lie between a pair of flaps on the other part. The flaps on one part are secured to the other 85 part by means of buttons and button holes 16 or any other suitable fastening means.

It will be seen that the extension may be easily put in position to provide a double bed which will be just as comfortable as the 90 ordinary double bed. When not in use the extension may be easily detached and placed under the bed to be out of the way.

Having described my invention what I claim is:—

In combination with a bed having slots in one side rail, an extension frame having staples on one of the side rails and engaging said slots, hooks carried by the side rail of the bed for engaging said staples, legs pivotally connected with the outer side of the extension frame and adapted to be swung upwardly against the end pieces of the extension frame, catches for holding said legs in folded position and rollers on the side 100 rails of the extension frame for permitting the said extension frame to be rolled under the bed when not in use.

In testimony whereof I affix my signature.

CELESTIA M. WINN.
